No. 12,820.

PATENTED MAY 8, 1855.

B. HARDINGE.

FACING BED FOR GRINDING ARTIFICIAL GRANITE, &c.

UNITED STATES PATENT OFFICE.

BENJ. HARDINGE, OF NEW YORK, N. Y.

FACING-BED FOR GRINDING ARTIFICIAL GRANITE, &c.

Specification of Letters Patent No. 12,820, dated May 8, 1855.

To all whom it may concern:

Be it known that I, BENJAMIN HARDINGE, of the city of New York, in the county and State of New York, have invented a new and Improved Machine for Facing Concrete Conglomerate, Variegated Artificial Granite, and other Hard Substances, which machine I call a "Facing-Bed," which I verily believe has not been known or used before; 10 and I do hereby declare that the following is a full and exact description thereof, reference being had to the accompanying drawings and the figures and letters of reference marked thereon:

15 The nature of my invention consists in constructing a round, cast iron, saucer-shaped dish, of about 8 feet in diameter, and filling it with concrete cement of silici-calcareous and ferruginous frit; ground 20 and mixed with coarse crude emery, steel turnings, sharp sand and hydrous silicates, with which it is wet up into a plastic state, put into said dish; and leveled with a straight edged spatula, while in very slow 25 motion; so that, when hard, it turns in a perfect horizontal level, and runs as true as though it were turned in a lathe from a solid. And the precautionary manner of suspending it with the shaft which carries 30 it, giving it (by heavy steel bearings) a slight vertical elasticity, prevents the smallest sudden jerking, common to ordinary processes of this manner of grinding.

To enable others skilled in the art to make 35 and use my invention, I will proceed to describe its construction and operation.

I construct a circular dish of cast iron of about 8 feet diameter with its periphery turned up, A, and B, (or a saucer shape) 40 thus forming a strong dish, which is bolted to cast iron supporters D. These are secured to the upright shaft E, which turns in between, and rests upon two heavy bolsters of steel in thick leaves, F, with collars, G, as 45 bolsters and bush for the shaft, E, to turn in. The ends of these springs, F, rest upon cross pieces mortised into the beams, P, P. There is a gudgeon at the lower end of the shaft, E, which is steel pointed, which rests 50 and turns in and upon the socket, I, which is bolted to a steel bolster (also in leaves) to afford a very slight elasticity J, which is

let into the plumber-block, K. The shaft, E, is turned by the pulley and belt L, by a four-horse power of either steam, water, or 55 horses. Having my construction so far ready I proceed to fill my dish A, and B, with concrete cement; made of silici-calcareous and ferruginous frit, ground and mixed with coarse crude emery steel turn- 60 ings and sharp sand, wet up, with hydrous silicates, into a plastic mass; having filled said dish, I put in very slow motion the whole machine; in order to level down the aforesaid plastic mass, with a straight edge 65 spatula so that, when hard, it runs in as perfect a horizontal level as if turned in a lathe from a solid, and when perfectly consolidated and baked is ready for use.

The utility and indispensable necessity 70 of this machine will now at once be seen not only in facing substances so much harder than marble, and cutting them down so rapidly, (being fed with sharp sand and water in the usual manner) notwithstanding 75 a number of blocks of artificial conglominate composed of quartz pebbles of all sizes (oval shaped) variegated granite paving stones, interspersed with mica and the interstices filled also with silicious materials, 80 could not be ground by any of the processes heretofore in use; and the facing is necessary to produce the beauty and effect of a sawed natural formation, admitting that a secondary, or even a primitive formation of 85 such beauty and hardness could be found and sawed. The finish and polish of my faced stone is by a transparent lava not here described.

I claim—

1. The above described artificial grind- 90 stone or facing-bed, consisting of a saucer shaped dish filled with a concrete of the materials specified or others substantially the same.

2. Also the suspension of the shaft, which carries the rotary facing-bed upon steel supporters substantially as and for the purpose above set forth and described.

BENJAMIN HARDINGE.
